UNITED STATES PATENT OFFICE.

FRANK H. DE BRUN, OF CHICAGO, ILLINOIS, ASSIGNOR TO THE NECEDAH MANUFACTURING CORPORATION, OF NECEDAH, WISCONSIN, A CORPORATION OF WISCONSIN.

POWER-PLANT MOUNTING.

1,389,424.

Specification of Letters Patent. Patented Aug. 30, 1921.

Application filed July 29, 1920. Serial No. 399,957.

To all whom it may concern:

Be it known that I, FRANK H. DE BRUN, a citizen of the United States, residing at Chicago, in the county of Cook and State 5 of Illinois, have invented certain new and useful Improvements in Power-Plant Mountings, of which the following is a specification, reference being had to the accompanying drawings, and to the reference 10 characters marked thereon, which form a part of this specification.

It very frequently happens that persons using small power plants have occasion to operate different mechanisms, located at 15 somewhat widely separated points, and find it desirable to have the motor engine portable. For example, a farmer may have the dynamo of his lighting plant in one location, his centrifugal creamers and other machinery in other locations. It is, manifestly, 20 expensive to use a plurality of power plants or engines to run the separate machines.

One difficulty experienced in moving portable engines from one location to another has been the inability to stabilize the base of the engine in the several locations, in order to produce the best results.

The principal object of this invention is to produce a power plant mounting that 30 may be used in a fixed position adjacent to the particular machine to be operated by the engine, each mounting so arranged as to properly support a carriage or truck upon which the engine is to be mounted, and so 35 arranged that when the carriage is rolled upon a particular base or mounting, the carriage and its engine will be raised from the base line or ground sufficiently to raise the wheels of the carriage therefrom and 40 transfer all of the weight of the engine and carriage directly to the mounting.

The details of my invention and its many advantages will be apparent as I proceed with my specification.

45 In that form of device which I have chosen to illustrate my invention, as shown in the accompanying drawings, Figure 1 illustrates in a side elevation the dynamo of a lighting plant, an engine mounting adjacent thereto and the power plant and carriage upon and secured to said mounting.

Fig. 2 is an end elevation of the same.

Fig. 3 is a side elevation of the same with the engine and carriage removed from the mounting.

Fig. 4 is a side elevation of the engine and carriage upon a mounting.

Fig. 5 is a plan view of the structure shown in Fig. 3.

Fig. 6 is a plan view of a slightly modified form illustrating one means of directing the carriage properly to the mounting.

Fig. 7 is a vertical sectional view, enlarged, of a detail showing one means of securing the carriage to the mounting.

In said drawings, A represents as a whole, a dynamo of a lighting plant, provided with a base a, suitably bolted to a fixed foundation block F. B represents as a whole, the power plant or engine mounted upon the usual hollow pedestal b and adapted to be suitably bolted to the top or table surface of a carriage C.

The dynamo A is provided with a transverse shaft 1 carrying on one of its ends a coupling gear 2. A shaft 3 on the power plant is provided with a spur gear 4 adapted to mesh with and operate the spur gear 5. This gear 5 is mounted upon a rotatable sleeve 6 which latter may be eccentrically mounted upon a transverse shaft, not shown in the drawing. To the outer end of said sleeve 6 is secured a coupling or gear 7, adapted to engage the coupling or gear 2 of the dynamo A. 8 is a handle attached to the coupling 6 and adapted to be moved so as to place the gears 4 and 5 in mesh, as shown in Fig. 1, or to raise the gear 5 out of mesh with the gear 4 as shown in Fig. 4. The shaft 3 is provided with the usual fly wheel 9 and may also be provided with a pulley wheel 10. The crank 11 enables the operator to start the engine in the usual manner.

The carriage C will conform in general dimensions to the base of the engine to which it is bolted, and comprises two longitudinal side members 12, 12, and transverse connecting members 13. The side members 12 have inwardly directed flanges 14, the top surfaces of which constitute a bearing surface for the base of the engine. The under surfaces of similar inturned flanges 15 provide a shoulder or support for the car-

riage C, when it rests upon the mounting presently to be described.

In said under surfaces of the flanges 15 is cut a longitudinally extending recess or 5 groove 16 adapted to engage a track 17. Preferably the contour of the recess 16 and of the block 17 will be complementary.

The carriage mounting, characterized as a whole by the letter M, comprises two side 10 bars or supports 18, preferably of channel iron, with their flanges directed inwardly; the side bars 18, 18, being joined by connecting cross bars 19. In some cases, the mounting M may be integral with the foundation 15 block F, as for example in the form shown in Figs. 1 and 3. In other instances, the mounting M will terminate at one end with a back stop S. The two side members 18, 18, of the mounting M, are in parallel relation, as clearly indicated in Figs. 2, 3 and 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450

G indicates the ground line on which the mounting M rests. At either side of the front ends 20 of the mounting M, I place suitable guide bars 22. The carriage C will be provided at each side with rotatable wheels 23 mounted upon axles 24 whereby the power plant and carriage may be moved from one place to another along the ground line G when the power plant and carriage are disengaged from the mounting M. When the carriage C is upon the mounting M the height of the tread of the rails 17 above the ground will be such as to clear the tread of the wheels 23 from the ground. 25 is any suitable wheel or draw bar that may be secured to the carriage C and by which the carriage may be moved bodily along the tracks 17 and down the inclines 21 until the wheels 23 engage the ground G in restoring the carriage to the mounting M. The latter will be approached from the ends 20 as indicated by the dotted wheel lines 23, the wheels passing in the space between the guides 22 and the side bars 18. Presently the carriage will contact with the inclined surface 21 and the carriage will be pushed forward until the grooves or recesses 16 engage the tracks 17.

In the modification shown in Fig. 6, I have dispensed with the side guide bars 22, 22, and formed guiding surfaces 26 upon the outer edges of short extensions 27 to the side members 18. In Fig. 6, the first or approach position of the wheels 23 of the carriage is indicated in full lines and the final position indicated in dotted lines, whereby it will be seen that in moving the carriage toward and longitudinally of the

mounting M, the carriage wheels will contact with one or the other of said guide surfaces 27 and thus properly center the carriage with respect to the mounting M so that the grooves 16 will engage the tracks 17. 70

To secure the carriage C upon the mounting M, any suitable mechanism may be employed. I have, however, illustrated a simple mechanism, the detail of which is more clearly shown in Fig. 7, comprising a downwardly projecting flange member 28 from each of the outside bars 12 of the carriage. These two flanges 28 will straddle the two side members 18 of the mounting M. A set screw or locking bolt 29, operated by the handle 30 will be passed through the flanges 28 until the end of the set screw 29 will impinge against the surface of the side bar 18; thus the carriage C may be conveniently and securely locked to the mounting M. 85

It is recommended that a plurality of mountings M will be used in connection with one power plant and carriage C and that said mountings will be placed at different places about the factory or farm where different machines are conveniently located. 90

The purpose of the pulley wheel 10 is to enable the user to place a belt thereover and thus couple the power plant with the machine which is desired to be operated by said power plant. The pulley 10 may, obviously, connect the power plant with the dynamo A, but I prefer the direct coupling indicated by the coupling or gears 2, 7, as indicated in the drawing. 100

As shown, the carriage C is of the relative size of the base of the power plant B and the power plant and carriage will be manipulated by the draw bar or handle 25. Obviously the axles 24 of the carriage C 105 may be directly connected with the power plant in a familiar manner so that the carriage C may be operated by the power plant if desired.

It will be manifest from the foregoing 110 that when the power plant is coupled up with the dynamo A and the carriage C locked by the bolts 29, to the mounting M, with the tracks 17 filling the longitudinally arranged grooves 16, the engine and base will 115 have a firm, secure and rigid position not only with respect to the mounting M but to the machine (in this instance, the dynamo) which it is to operate. Similarly, when the carriage C and the engine B are moved over 120 onto the mounting illustrated in Fig. 4, and in juxtaposition to another machine to be operated from the pulley 10, the engine and carriage will be securely and practically held for all operative purposes; the carriage 125 being locked by the bolts 29 to the mounting M while the end of the carriage rests squarely against the stop or abutment S. It will be understood of course that in all cases the mounting M is of such size and weight as to 130

rest rather securely by gravity upon the ground but it will also be clearly understood that the several mountings M may be locked to or built up from the ground in a familiar manner.

5 I claim as my invention:

1. The combination with a stationary member provided with a carriage mounting, of an engine carriage adapted to support the engine independently of said stationary member and also adapted to be supported upon said mounting, and means for locking the carriage and the stationary member together.
- 10 2. The combination with a stationary member provided with longitudinally arranged carriage tracks, of an independently operated carriage and adapted to ride upon said tracks and means for locking the carriage and stationary member together.
- 15 3. In a construction of the class described, adapted to support a motor engine, of a carriage mounting provided with a carriage track longitudinally thereof, a back stop at one end of said track and a downwardly inclined surface at the other end of said track and means for locking the carriage when on the track to said mounting.
- 20 4. In a construction of the class described, adapted to support a motor engine, of a carriage mounting provided with a carriage track longitudinally thereof, a back stop at one end of said track and a downwardly inclined surface at the other end of said track and means for locking the carriage when on the track to said mounting.
- 25 5. Complemental engaging surfaces between the carriage and the track, and means for lock-

ing the carriage when on the track to said mounting.

5. In a construction of the class described, adapted to support a motor engine, of a carriage track longitudinally thereof, a back stop at one end of said track and a downwardly inclined surface at the other end of said track and means for locking the carriage when on the track to said mounting, said means comprising downwardly projecting flanges, on the carriage, adapted to straddle the outside margins of the mounting and a screw bolt passing through said flanges and contacting with said outside margins of the mounting.

6. In a construction of the class described, adapted to support a motor engine, of a carriage mounting provided with a carriage track longitudinally thereof, a back stop at one end of said track and a downwardly inclined surface at the other end of said track and means for locking the carriage when on the track to said mounting, and guides outside of the inclined ends of the mounting adapted to center the carriage upon the mounting as the carriage approaches said mounting.

In testimony that I claim the foregoing as my invention I affix my signature, in the presence of two witnesses, this 27th day of July, 1920.

FRANK H. DE BRUN.
